DESIGN FOR A SALT SHAKER

Vincent A. Kasin, Hollywood, Calif.

Application February 18, 1947, Serial No. 137,000

Term of patent 14 years

(Cl. D44—22)

To all whom it may concern:

Be it known that I, Vincent A. Kasin, a citizen of the United States, residing at Hollywood, in the county of Los Angeles and State of California, have invented a new, original, and ornamental Design for a Salt Shaker, of which the following is a specification, reference being had to the accompanying drawing, forming part thereof.

I claim:

The ornamental design for a salt shaker, substantially as shown.

VINCENT A. KASIN.
